United States Patent Office.

FREDERICK WALTON, OF STAINES, ENGLAND.

Letters Patent No. 91,289, dated June 15, 1869; patented in England, December 11, 1868.

IMPROVED MODE OF CONSTRUCTING HOUSES

The Schedule referred to in these Letters Patent and making part of the same.

To all to whom it may concern:

Be it known that I, FREDERICK WALTON, of Staines, in the county of Middlesex, England, a subject of the Queen of Great Britain, have invented or discovered new and useful "Improvements in the Construction of Houses and other Buildings or Structures;" and I, the said FREDERICK WALTON, do hereby declare the nature of the said invention, and in what manner the same is to be performed, to be particularly described and ascertained in and by the following statement thereof; that is to say—

This invention has for its object improvements in the construction of houses, and other buildings or structures.

I construct a light building, requiring only comparatively unskilled labor in its erection, and but little foundation, and which is very dry and warm, in the following manner:

I take a number of narrow planks, and place them horizontally, one over the other, separating them, the one from the other, by placing, at intervals, blocks, or short uprights between them. In this way a frame of the desired dimensions is produced, the blocks being arranged in vertical lines, and the frame being firmly bound together by long bolts, passing from top to bottom of it. Each bolt is passed close alongside of, or it may be through a vertical line of blocks.

The frame may be lathed and plastered on both sides, or wicker-work hurdles may be fixed upon it to receive the plaster, or it may be planked, or otherwise closed.

In place of wood planks and blocks, other materials may, in some localities, be advantageously substituted. Thus, for the planks, sheet-iron, bent to a trough-like form, may be used, and for the blocks, lengths of iron tube may be substituted. Earthenware tubes may be similarly used, as may also cement, or concrete blocks. These blocks may be made so large as themselves to close the frame. They should then, for lightness, be cast hollow.

Blocks for this purpose may also, very advantageously, be made of cork-dust mixed with plaster of Paris. Thus, a very light block may be obtained. Sawdust may be similarly used.

In order that my said invention may be most fully understood, and readily carried into effect, I will proceed to describe the drawings hereunto annexed.

Description of the Drawings.

Figure 1 is an elevation of part of the frame of a building, constructed according to my invention.

a a is a wooden sill, which may frequently rest directly on the soil, if it be first prepared by well ramming it.

On this sill the flooring-joists *b b* are fixed.

c c are the planks, placed parallel, the one with the other, and kept apart by the blocks *d d*.

The openings for windows and doors are obtained by using short planks, *c'*, (not allowing them to run through,) as the drawing shows.

e e are the screw-bolts and nuts, by which the parts of the frame are drawn firmly together. These bolts pass from the sill-plate *a* to the roof-plate *f*.

Figures 2 represent a portion of a similar frame, constructed of iron, in the manner already stated.

Filletts of wood are fixed at the edges of the horizontal iron plates, to receive the lathing and plastering, or other methods may be resorted to for closing the frame, as already described.

Figures 3 show a moulded block, it may be of cork-dust, or sawdust and plaster, adapted to fill the openings in the frame. It is made with a lip to overlap and cover the blocks *d*; or moulded blocks of this sort may be substituted for the blocks *d*, the bolts *e* passing through them.

Having thus described the nature of my said invention, and the manner of performing the same, I would have it understood that what I claim as my improvements in the construction of houses, and other buildings or structures, is—

The combination of the planks or pieces *c*, blocks *d*, and bolts *e*, substantially as herein described.

FRED. WALTON.
